UNITED STATES PATENT OFFICE.

ROLLAND R. RECK, OF BRADFORD, PENNSYLVANIA, AND CHARLES S. ALT, OF BUFFALO, NEW YORK, ASSIGNEES TO BUFFALO GASOLENE MOTOR COMPANY, A CORPORATION OF NEW YORK.

CARBURETOR.

Application filed November 29, 1924. Serial No. 752,967.

This invention relates to a carburetor and has the object to provide in connection with a carburetor, means for permitting the use of natural gas or manufactured gas with or 5 without the use of gasoline, thereby rendering it possible to use whatever fuel is available without requiring any change in the construction of the carburetor.

In the accompanying drawings:—

10 Figure 1 is a vertical section of a carburetor embodying our improvements. Figures 2 and 3 are horizontal sections taken on the correspondingly numbered lines in Figure 1.

15 Similar characters of reference indicate like parts throughout the several views. The numeral 10 represents a mixing chamber which in the present instance is provided on its upper end with an upwardly 20 opening mixture outlet 11 containing a butterfly valve 12 and on its lower part with a laterally extending air inlet 13 containing a butterfly valve 14. Between its inlet and outlet the mixing chamber is provided with 25 a large Venturi tube 15 the bore of which flares upwardly and arranged axially within the mixing chamber and the lower part of the large Venturi tube is a small vertical Venturi tube 16 which opens at its upper end 30 into the large Venturi tube while its lower end is open and adapted to communicate with a gas supply and its side is provided with a plurality of liquid fuel supply openings 17. The small Venturi tube is supported from the adjacent wall of the mixing chamber by an arm 18 and its liquid fuel openings are connected with the supply chamber 19 of a gasolene or similar liquid fuel supply device by means of a conduit 20

35 extending through the arm 18 and the walls of the mixing liquid fuel supply chamber and containing a regulating valve 21. The liquid level may be maintained at the proper height in the liquid fuel supply chamber 40 by a valve 22 controlling the inlet 23 of the liquid supply chamber and a float 24 arranged within the liquid fuel supply chamber and connected with the valve 22.

45 Our improvements which are associated with an ordinary carburetor, of which the foregoing description is merely an example, may be embodied in various forms, that shown in the drawings being satisfactory and constructed as follows:—

The numeral 25 represents a gas supply tube whereby either natural or manufactured gas is supplied to the small Venturi tube so that the carburetor can be used either with a liquid fuel, or a gaseous fuel, or a combination of these fuels. This gas supply tube is arranged vertically in the lower part of the mixing chamber and extends through the lower side thereof so that its upper end is arranged close to the lower end of the small Venturi tube and communicates therewith but still leaves the lower end of the Venturi in communication with the air inlet 13, while the lower end of the gas supply tube projects to the exterior of the mixing chamber. The gas supplied to this 55 gas tube 25 is directed to the lower end of the small Venturi tube and as it issues from the latter it mixes with the air entering through the inlet 13 and forms a combustible mixture therewith in the large Venturi tube which is discharged therefrom through the outlet 11 to the place of consumption. At this time the valve 21 may be closed so that the carburetor only mixes air and gas. If desired the valve 21 may be opened while 60 gas is being supplied to the pipe 25 in which case both gas and gasolene or other liquid fuel are mixed simultaneously with air 65 preparatory to consuming the mixture in a gas engine or elsewhere.

In order to permit of either cutting off the supply of gas through the gas supply tube 25 or regulating the flow of gas through the same a valve device is provided which in its preferred form is constructed as follows:—

The numerals 26, 27 represent the upper and lower sections of a valve casing, the upper section being connected with the lower end of the gas supply pipe or tube 25 and the lower section being provided with a laterally projecting inlet nipple 28 which receives a supply of natural or artificial gas from any available source. Between the upper and lower sections of the gas controlling valve casing the same is provided with a partition 29 having an upwardly flaring valve seat 30. A downwardly tapering valve plug 31 is arranged in the valve casing and movable axially toward and from the valve seat 30 so as to either engage the same for closing this valve or to be arranged in a more or less open position, depending upon the conditions under which

the carburetor is used. In its preferred form the means for adjusting the plug of the gas controlling valve comprises a valve stem 32 projecting from the small end of the gas valve plug 31 downwardly through the lower side of the gas valve casing, an adjusting screw nut 33 arranged on the lower end of this stem and adapted to engage the underside of the gas valve casing for limiting the lifting action of the gas valve plug and a lock nut 34 also arranged on this stem and engaging with the underside of the adjusting screw nut. The position of the valve plug 31 relatively to the valve seat 30 is adjusted for regulating the supply of gas through this valve by means of a vertical adjusting screw 35 engaging with the lower end of the valve stem 32 and working in a support 36 depending from the valve casing and a clamping nut 37 arranged on said adjusting screw and engaging with the lower end of said support, as shown in Figure 1.

When the gas supply device is used the adjusting screw is turned up so that the valve is slightly unseated and permits the desired amount of gas to pass the valve plug to the carburetor, but when this valve is not used the screw 35 may be turned so as to permit the valve plug 31 to close entirely. If the suction on the outlet of the carburetor lifts the valve plug 31 the latter is prevented from being raised unduly and closing the outlet of the gas valve casing by engagement of the stop screw 33 with the underside of the valve casing before the plug 31 strikes the top of this casing.

By thus combining with the usual carburetor for liquid fuels a device which also permits gaseous fuels to be used in the same carburetor, it is possible to use the same

carburetor either with a gaseous fuel, or a liquid fuel as circumstances may require. This carburetor is therefore particularly desirable for use on gas engines for operating gas and oil well drilling outfits, inasmuch as it permits of economical operation of the power plant by utilizing the natural gas available in the vicinity of the power plant.

For the purpose of permitting the gas to be cut off from the supply pipe 25 the inlet 28 is provided with a valve of any suitable construction and when this valve is closed any lifting effect which is exerted on the conical valve 31 due to suction in the tube 15 is idle and will not produce any results.

We claim as our invention:—

A carburetor having a gas supply pipe, a valve casing provided at one end with an outlet communicating with said gas supply pipe, at its side with a gas inlet and between its inlet and outlet with an upwardly flaring conical valve seat, a conical valve plug arranged within the valve casing and movable axially toward and from said valve seat for controlling the flow of gas therethrough, a valve stem extending from the lower small end of said conical valve plug downwardly through the lower end of said valve casing, a screw nut arranged on the lower end of said valve stem and adapted to engage the underside of said valve casing, a support arranged on the lower part of said valve casing, and an adjusting screw arranged on said support and adapted to be engaged by the lower end of said valve stem for arresting the outward movement of the conical valve at a predetermined distance from its seat.
